(57) **CLAIM**

The ornamental design for a beverage cap opener, as shown and described.

DESCRIPTION

FIG. 1 is a perspective view of a beverage cap opener.

FIG. 2 is a top plan view of the beverage cap opener.

FIG. 3 is a right side elevational view of the beverage cap opener.

FIG. 4 is a bottom plan view of the beverage cap opener.

FIG. 5 is a left side elevational view of the beverage cap opener.

FIG. 6 is a front elevational view of the beverage cap opener; and,

FIG. 7 is a rear elevational view of the beverage cap opener. The broken lines depict environmental subject matter only and form no part of the claimed design.
